UNITED STATES PATENT OFFICE.

WILLIAM D. BARTLETT AND SYDNEY MARQUIS, OF CLEVELAND, OHIO, ASSIGNEES OF
ONE-FOURTH TO CHARLES E. THOMPSON AND ONE-FOURTH TO J. ALBERT KRIDER,
OF CLEVELAND, OHIO.

CENTERING DEVICE.

1,402,720.

Specification of Letters Patent.

Patented Jan. 3, 1922.

Application filed October 11, 1919. Serial No. 330,117.

To all whom it may concern:

Be it known that we, WILLIAM D. BARTLETT and SYDNEY MARQUIS, citizens of the United States, residents of Cleveland, county of Cuyahoga, and State of Ohio, have invented new and useful Improvements in Centering Devices, of which the following is a specification, the principle of the invention being herein explained and the best mode in which we have contemplated applying that principle, so as to distinguish it from other inventions.

Our invention relates to centering devices and particularly to devices of this nature utilized for securely clamping blanks, in which centers are to be formed, in a chuck and then feeding a rotating drill to and from said blanks, thus performing the centering operation, it being designed that the blank shall later be turned or ground upon said centers. Particularly, our invention relates to centering devices utilized for drilling centers in the heads and the stems of valves.

The annexed drawings and the following description set forth in detail certain means embodying our invention, the disclosed means, however, constituting but one of the various mechanical forms in which the principle of the invention may be applied.

In said annexed drawings:

Figure 1 represents a longitudinal vertical section of our improved centering device, taken in the plane indicated by the line I—I, Figure 3, and showing the drill removed from the work;

Figure 1^a represents a fragmentary longitudinal vertical section, taken in a plane different from that in which Figure 1 is taken, and particularly showing a certain section of a cam shaft, hereinafter fully described, and certain related elements;

Figure 2 represents a side elevation, with parts in section, showing the several elements in drilling position;

Figure 3 represents a right hand end elevation of the device, with parts in section;

Figure 4 represents a vertical transverse section, taken in the planes indicated by the line IV—IV, Figure 2;

Figures 5 and 6 represent transverse vertical sections, taken in the planes indicated by the lines V—V and VI—VI, respectively, Figure 1.

Figure 7 represents a fragmentary ver-

tical longitudinal section, taken in the plane indicated by the line I—I, Figure 3, showing the chuck thrown back from working position and the work removed;

Figures 8 and 9 represent, respectively, perspective views of an outer sleeve member and an inner sleeve member, utilized in our centering device;

Figures 10 and 11 represent, respectively, perspective and end views of a cam shaft forming part of our invention.

Figures 12 and 13 represent, respectively, side and end views of a collet utilized in our invention.

Referring to the annexed drawings, there is indicated by the ordinal 14 the tail-stock of our improved centering device mounted in a general frame work 1, the head-stock being indicated by the ordinal 9. It is designed that by suitable means hereinafter fully described a sleeve 2 connected to a spindle 3 by means of key 15, to which spindle 3 is secured a drill 4, shall be rotated, and that the whole tail-stock 14 including said elements 2, 3, 4, and other related elements hereinafter mentioned shall be fed forward to effect the centering operation in the work which is here illustrated by a valve having the stem 5, the head 6 and the stem end 7. By means hereinafter fully described the work 5, during the drilling operation, is securely clamped in a chuck 8 mounted in the head-stock 9. The means for effecting the feeding operation include a feeding lever 10 and the means for effecting the work-clamping operation include a clamping lever 11. A pulley actuated by any suitable source of power (not shown) is indicated by the ordinal 13.

The drill 4 may be adjusted longitudinally of the sleeve 2 by the means now to be described. It will be noted that the drill 4 is adapted to be clamped within a collet 17, one end of the latter being internally threaded to cooperate with the threaded inner end of the spindle 3, the latter being also threaded at its outer end to cooperate with an adjusting nut 16. In order to prevent the sleeve 2 from rotating when adjusting the spindle 3, we provide a pin 18, Figures 5 and 6, so spring-actuated as normally to be held in inoperative position, which pin is adapted to be forced against the action of the spring into a hole 19 formed in a sleeve 20 connected to the

sleeve 2 in a manner hereinafter fully described. The pin 18 is temporarily locked in such operative position by means of a bayonet lock 18', Figure 5.

5 Sleeves 2 and 20 are rotatably connected by means of a key 21, sleeve 20 in turn being rotatably connected to the pulley 13 by means of a key 35. Sleeve 2, however, can move longitudinally of the sleeve 20, 10 key 21 being secured to the sleeve 2 and sliding in an elongated key-way 34 formed in the sleeve 20 during the relative longitudinal movements of the sleeves 2 and 20.

The main rotating elements in the tail- 15 stock include those heretofore described. Four sets of ball races are provided, as plainly shown in Figure 1, and the moving races are indicated by the ordinal 22. The stationary races are indicated by the ordinal 20 24, of which two are secured in the main frame 1 to the rear of the tail-stock 14 and hence are not longitudinally movable and two are secured in the longitudinally movable tail-stock 14. The balls for the races are 25 indicated by the ordinal 23 and the lock nuts in each case by the ordinal 25. Screws 27 are utilized for securing the lock nuts after the races have been positioned. It is evident that there are relatively moving opposed 30 surfaces in the respective lock nuts 25 and the respective moving races 22 so that a slight clearance or recess 26 is provided between the same, as plainly shown in Figure 1. The forward moving race 22 is positioned 35 at its rear against the face of nut 28 screw-threaded to the sleeve 2, the cooperating stationary race 24 abutting against a shoulder of the tail-stock 14. The rear two sets of races abut, respectively, against shoulders formed 40 in the rotatable sleeve 20 and the main frame 1, and the two rear parts of the rear pair of the forward sets of races abut, respectively, against shoulders formed in the rotatable sleeve 2 and the non-rotatable tail-stock 14. All of these details are 45 plainly apparent in Figure 1, as also means for lubricating the various elements.

Formed in the bottom surface of the tail- 50 stock 14 is a rack segment 29 adapted to mesh with a pinion 30 mounted upon a square shaft 31, to an outer extending end of which shaft is secured the feeding lever 10. The other end of said shaft 31 comprises a round section 36 which is rotatably mounted in 55 the main frame 1, Figure 5. Mounted in a recess 37 formed in the pinion 30 and secured at one end to said pinion and at the other end to said main frame 1 is a torsion spring 32. It is evident from the foregoing de- 60 scription and the accompanying drawings that the actuation of the feeding lever 10 from the position shown in Figure 1 to the position shown in Figure 2 will result in the forward movement of the tail-stock 14 65 and consequently the drill 4 toward and into

the work 6 to complete the centering operation, the release of the feeding lever 10 resulting, through the tension to which the spring 32 is subjected, in the return of the tail-stock to the position shown in Figure 1. 70

During the drilling operation, the work is securely clamped in a collet 41 mounted in the chuck 8 and formed with a plurality of gripping surfaces. The means for effecting the clamping and unclamping of the work, as 75 well as means for throwing the chuck 8 out of working position, if desired, will now be described in detail.

The clamping lever 11 is secured to square-end portions 42 and 42' of two shafts rotatably mounted by means of round portions 43 and 43' in the chuck 8, suitable bearing surfaces 45 and 45' being provided, as plainly shown in Figure 4, the clamping lever 11 serving to actuate both sets of shafts by means of 80 the strap 11' connecting the lever 11 proper and the square end portion 42', Figure 4. The inner ends of the shafts 42 and 42' are formed with cam surfaces 44 and 44', the sections formed with these surfaces being elliptical 85 in cross-section. These cam ends of the shafts intersect inner and outer sleeves 50 and 51, respectively, mounted in the chuck 8, said sleeves being formed with opposed slots 50' and 51', respectively, adapted to 90 receive said cam shafts 44 and 44', said slots 50' and 51' registering in varying degrees for certain purposes hereinafter fully described. When the collet 41 is unlocked, the position of the cam shafts 44 100 and 44' is varied 90° from the position shown in Figures 1^a and 10, i. e., the major axis of the ellipse lies in a vertical plane. In this position sleeves 50 and 51 register to an extent substantially equal to the minor axis 105 of the ellipse. It will be evident from Figures 8 and 9 that the end walls of the slots 50' and 51' are, respectively, curved surfaces, 50² and 51² and plain surfaces 50³ and 51³ and that said surfaces, respectively, are 110 reversed in the slots 50' and 51'. The reason for this structure will be hereinafter described in detail.

The collet 41 is a double cone collet provided with beveled surfaces 46 and 48, respectively, the surface 46 being formed at one end and cooperating with a collet nut 47 screw-threaded to the outer sleeve 51, and the inclined surface 48 being formed at the other end and cooperating with a collet nut 49 screw-threaded to the inner sleeve 50. It is evident that the movement of the cam shafts 44 and 44' from a position in which the major axes of the ellipses lie in a vertical plane to a position illustrated by Figures 10 120 and 11, will result in the actuation of the outer sleeve 51, through the pressure of the cam shafts 44 and 44' against the walls 51³, from the position shown in Figure 7 to the position shown in Figure 1, i. e., from right to 125 130

- left, resulting in a clamping of the right hand end of the collet 41, through the medium of the cooperating surfaces 46 and 47, the left hand end of the collet 41 at the same time 5 also being clamped through the movement of the inner sleeve 50 from left to right, consequent upon the cooperation of the members 44, 44', 50³, 48 and 49. A collet spring is indicated by the ordinal 52.
- 10 In addition to the above described clamping action effected in the head-stock 9, the chuck mounted therein is pivotally supported so as to be capable of being thrown back out of working position, when the work 15 is of such a nature that it cannot be inserted in and removed from the chuck in the normal working position of the latter. This is true, for instance, when centering the head 6 of valves 5. This pivotal movement 20 of the chuck 8 out of position is also effected by the clamping lever 11. The pivotal movement takes place upon a pair of pivot pins 53 mounted in brackets 54 formed in the main member 1, as plainly shown in 25 Figure 3, there being provided suitable bushings 53'. The position in which the chuck is thrown back is illustrated in Figure 7, heels 56 formed on the chuck being adapted to strike stops 57 to limit the movement.
- 30 When the chuck is thrown back into position, the movement is limited by a stop surface 55.
- When work such as the stem end 7 is being centered, the same can be inserted in and 35 removed from the chuck 8 without throwing the latter back, and, in order that the chuck may be positively held from being thrown back during the collet unclamping action of the lever 11, pins 58 are provided which 40 intersect brackets 54 and are adapted to be threaded inwardly of said brackets so as to intercept heels 56 of the chuck 8 and thus positively retain the latter in its working position.
- 45 What we claim is:
1. In a head-stock, the combination of a body member; a chuck pivotally mounted therein; means for effecting the pivotal movement of said chuck; and a collet supported in said chuck, the means effecting the pivotal movements of said chuck also being adapted to effect the tightening and loosening of said collet.
  2. In a head-stock, the combination of a body member; a chuck pivotally mounted therein; means for effecting the pivotal movement of said chuck; a movable sleeve supported in said chuck; a collet adapted to be tightened or loosened by the movements 55 of said sleeve; and a rotatable shaft formed with a cam portion adapted to cause the movements of said sleeve, the means for effecting the pivotal movements of the chuck also being adapted to effect the rotation of said shaft.
  3. In a head-stock, the combination of a body member; a chuck pivotally mounted therein; means for effecting the pivotal movement of said chuck; relatively movable inner and outer sleeves supported in said chuck; a collet adapted to be tightened or loosened by the movements of said sleeves; and a rotatable shaft formed with a cam portion adapted to cause the movements of said sleeves, the means for effecting the pivotal movements of the chuck also being adapted to effect the rotation of said shaft.
  4. In a head-stock, the combination of a body member; a chuck pivotally mounted therein; means for effecting the pivotal movement of said chuck; a collet supported in said chuck, the means effecting the pivotal movements of said chuck also being adapted to effect the tightening and loosening of said collet; and means for preventing, if desired, the pivotal movement of said chuck when loosening said collet.
  5. In a head-stock, the combination of a body member; a chuck pivotally mounted therein; means for effecting the pivotal movement of said chuck; a movable sleeve supported in said chuck; a collet adapted to be tightened or loosened by the movements of said sleeve; a rotatable shaft formed with a cam portion adapted to cause the movements of said sleeve, the means for effecting the pivotal movements of the chuck also being adapted to effect the rotation of said shaft; and means for preventing, if desired, the pivotal movement of said chuck when loosening said collet.
  6. In centering devices, the combination of a tail-stock and a head-stock; a main frame upon which said stocks are mounted, said tail-stock being longitudinally reciprocable of said frame; means for effecting the movements of said tail stock; drilling means mounted in said tail stock; a chuck pivotally mounted in said head stock; means for effecting the pivotal movements and the clamping movements of said chuck; and means adapted positively to limit the pivotal movements of said chuck.
  7. In centering devices, the combination of a tail-stock and a head-stock; a main frame upon which said stocks are mounted, said tail stock being longitudinally reciprocable of said frame; means for effecting the movements of said tail stock; drilling means mounted in said tail stock; a chuck pivotally mounted in said head stock; means for effecting the pivotal movements and the clamping movements of said chuck; means for preventing the pivotal movements of said chuck during its clamping movements, if desired; and means adapted positively to limit the pivotal movements of said chuck.
  8. In centering means, the combination of a tail stock and a head stock; a main frame upon which said stocks are mounted, said

tail stock being longitudinally reciprocable of said frame; means for effecting the movements of said tail stock; drilling means mounted in said tail stock; pivot pins mounted in said head stock and upon which said chuck is mounted; means for effecting the pivotal movements and the clamping movements of said chuck; and means adapted positively to limit the pivotal movements of said chuck.

9. In centering means, the combination of a tail stock and a head stock; a main frame upon which said stocks are mounted, said tail stock being longitudinally reciprocable of said frame; means for effecting the movements of said tail stock; drilling means mounted in said tail stock; pivot pins mounted in said head stock and upon which said chuck is mounted; means for effecting the pivotal movements and the clamping movements of said chuck; means for preventing the pivotal movements of said chuck during its clamping movements, if desired; and means adapted positively to limit the pivotal movements of said chuck.

10. In centering devices, the combination of a main frame; a head-stock mounted thereon; a chuck pivotally mounted in said head stock; a pair of rotatable shafts formed with cam portions intersecting the sides of said chuck; a clamping lever secured to said shafts; a pair of outer and inner sleeves mounted in said chuck, said sleeves being formed with laterally disposed slots adapted to be intersected by the cam portions of said shafts, said sleeves being relatively longitudinally movable; a split collet disposed within said inner sleeve, the turning of said cams in the slots of said sleeves being adapt-

ed to move the latter in opposite directions; means actuated by the movements of said sleeves to open and close said collet, the actuation of the means operating the sleeves also effecting the pivotal movements of the chuck; drilling means; and means adapted relatively to move said head stock and supported elements and said drilling means.

11. In centering devices, the combination of a main frame; a head stock mounted thereon; a pair of oppositely disposed pivot pins mounted in said head stock; a chuck pivotally mounted upon said pins; a pair of shafts mounted in said chuck and provided with inner cam portions extending inwardly of the chuck wall; means for rotating said shafts; a collet split at both ends disposed centrally of the chuck wall; inner and outer sleeves disposed intermediate said chuck wall and said collet, said sleeves being relatively longitudinally movable and formed with oppositely disposed slots adapted to be intersected by the inner cam portions of said shafts, said slots in the open condition of the collet being designed to register to receive said shaft cam portions in a certain position of the latter, the rotation of said shaft cam portions effecting the relative longitudinal movement of said sleeves; means actuated by said sleeve movements to close the collet, the actuation of the means operating the sleeves also effecting the pivotal movements of the chuck; drilling means; and means adapted to move the latter toward and from said head stock.

Signed by us, this 15th day of Sept., 1919. 75

WILLIAM D. BARTLETT.
SYDNEY MARQUIS.
